ELECTRONIC GONIOMETER FOR RADIO
DIRECTION FINDERS

John H. Newitt, Montclair, N. J., assignor to
Federal Telephone and Radio Corporation, New
York, N. Y., a corporation of Delaware

Application October 28, 1944, Serial No. 560,823

13 Claims. (Cl. 343—121)

This invention relates to new and useful improvements in goniometers and more particularly in goniometers co-operating with instantaneous direction indicators.

The main object of the invention is to maintain the indicator and the goniometer in synchronism. This is accomplished by deriving a voltage from the indicator to control the goniometer.

The invention is particularly applicable to goniometers and indicators operated by electronic means, although electro-mechanical indicators could be used if the rotating parts were operated to produce a synchronizing signal with which to control, e. g., the frequency of an oscillator initially supplying the modulation voltage of the goniometer. The oscillator should be adjusted to produce triangular or other saw-tooth wave forms for controlling frequency and phase synchronism.

These and other features of the invention will more clearly appear from the appended claims and the following detailed description of an embodiment illustrated in the drawings in which:

Fig. 1 is a complete block diagram of the indicator equipment, electronic goniometer equipment, and antenna array connected in accordance with this invention;

Fig. 2 is a diagram of the goniometer equipment and indicator equipment in block form, and an antenna array for use therewith in schematic form;

Figs. 3 and 4 are circuit diagrams of the electronic goniometer; Figs. 3a and 3b are diagrams explaining the functioning of the circuit of Fig. 3, and

Fig. 5 is a graph of a typical modulation schedule.

The electronic indicator as included in the block diagram of Fig. 1 comprises an oscillator 1, a synchronizing voltage source 2, an audio amplifier 3, a phase shifter 4, two D. C. amplifiers 5 and 6, and a cathode ray tube 8. The oscillator 1 produces in its output a sine wave of high precision in either of the following two ways:

(a) The oscillator may be of the phase shift type provided with a filter to produce substantially pure sine wave. Such an oscillator however cannot be synchronized from an outside source and could be used only where synchronism of the indicator is not needed.

(b) Where several indicators must be simultaneously operated, or where, for other reasons synchronism is desired, the oscillator should be one adapted to produce triangular or other saw-tooth wave forms and connected with an external

5 synchronizing source 2. The saw-tooth wave may be sent through a filter to produce a substantially pure sine wave.

A triangular type of saw-tooth wave is recommended since it is the easiest of the saw-tooth waves to filter. A "transitron" oscillator circuit, a negative resistive arrangement as described for example in "Radio Engineers Handbook" (F. E. Terman, first edition, 5th impression, pages 318-319), and in the "Fundamentals of Vacuum Tubes," by A. V. Eastman (second edition, 7th impression, pages 432-433) with a large value of capacity in its output can be made to produce a suitable triangular wave form when properly adjusted. Synchronization may be obtained by insertion of synchronizing signal on the oscillator control grid. However, any suitable method may be used to obtain the desired sine wave form.

20 The sine wave output of oscillator 1 is fed to an audio frequency amplifier 3 and then in one channel over a 90° phase shifter 4 to a D. C. amplifier 5, and in a second channel directly to a D. C. amplifier 6. These two channels are in 90° phase quadrature to one another. The output of amplifier 5 is connected to the horizontal and the output of 6 is connected to the vertical deflection plates of a cathode ray tube, an end view of which is indicated at 8.

25 When two sine wave voltages of 90° phase quadrature, but having the same frequency and amplitude are impressed on opposite plates of a cathode ray tube, the spot formed on the screen by the electron stream will describe a circle. The frequency of the circle will be equal to the frequency of the oscillator voltage producing it. Thus, a 30 cycles per second sine wave would cause the cathode ray tube spot to describe thirty complete circles each second.

30 The amplitude of the sine waves impressed on the deflection plates of the cathode ray tube determines the diameter of the circle produced. If the D. C. amplifiers 5 and 6 are biased to plate current cut-off, the circle will contract to a dot at its center. If, for instance, the output voltage 35 of a signal receiver 7 forming part of the system, Fig. 2, is used to bias the D. C. amplifiers to plate current cut-off condition, then the presence of a null would remove this bias and allow the circle to expand to its maximum diameter.

40 As well known, in mechanical goniometer systems for direction finding nulls are periodically produced by the continuous rotation of a rotor. In the bearing indicator of such system the circle will be pulled inward at every point, except where 45 the null occurs. This gives a directional indi-

cation because a sharp figure-of-eight pattern is produced by the spot of the indicator. Two reciprocal nulls occur during each electrical cycle.

The circle frequency is constant and the position of the nulls in relation to any point on the circumference of the circle changes with a change in direction of the received energy due to a redistribution of energy in the two sections of the antenna system. In other words, the goniometer balances for a null condition at different points during its rotation for different distributions of energy in the two sections of the antenna array. The nulls will move in relation to a point on the circle circumference in response to changes in antenna energy distribution caused by a change in direction of the received energy. The movement can be read on a calibrated scale located at the periphery of the circle.

The output of the electronic goniometer 13 (Figs. 1, 2 and 3) of the present invention is fed to the signal receiver 1. The device 13 electronically simulates the rotary action of the customary mechanical goniometer by the expedient of varying the gain of two pairs of electronic tubes 14, 15 and 16, 17 (Fig. 3) in a sine and cosine manner. The electronic goniometer 13 and an Adcock antenna array, 13a are included in Fig. 1 in block form to complete a direction indicating arrangement. This is accomplished by applying from a modulating signal source M (Figs. 1 and 2) sinusoidally varying voltages at M_1 to the plates of the linearly responsive tubes 16 and 17, and at M_2 to the plates of 14 and 15. The stability and linearity of the device are greatly improved by using plate modulation with A. C. only, rather than by the alternative method of superimposing an A. C. voltage on a grid bias voltage and applying D. C. to the plates.

Triode curves show the greatest $E_p - I_p$ linearity close to zero bias and the goniometer is operated close to this point at all times.

The goniometer makes use of a balanced input system comprising double coaxial cables 18, 19 whereby conventional directional arrays 20, 21 (such as an Adcock or crossed loops) may be used. Each section of the antenna array is fed into a pair of said tubes, 16, 17 and 14, 15, respectively. The inputs of each tube pair are cross connected over resistances R_5 , R_6 and R_7 , R_8 , respectively, between the grid and the cathode of the pair. The purpose of this is to operate only one tube of a pair at any one time since A. C. is applied to the plates over terminals M_1 and M_2 , tubes of each pair are 180° out of phase, while the pairs are 90° out of phase in respect to each other.

With such a cross connection arrangement, the voltages on transmission lines 18 and 19 are always impressed between grid and cathode of an active tube. If such a cross connection were not made, the active tube would receive only the voltage of the one transmission line to ground.

The transmission lines being terminated in low values of resistance, the grid resistance of one tube may serve as the cathode resistance of its pair. The back rectification of the grid of the inactive tube would maintain the bias on the grid of the active tube at exactly zero but for the small dividing resistors R_5 , R_6 , R_7 , R_8 , which insure a small bias and prevent the flow of grid current. The values of these resistances are small as compared to other circuit values and thus do not appreciably contribute to signal attenuation by voltage division.

The voltages of the transmission lines 18 and 19 appear across resistance R connected to the

outputs of the tubes over output coupling condenser C_1 , C_2 , C_3 , and C_4 .

The amplitude and phase relations are determined by the modulation schedule applied to the plates of the goniometer tubes. For example, as graphically shown in Fig. 5, when the modulating voltage is applied to tubes 16 and 17, it will rise from zero to maximum amplitude then drop back to zero, its phase will then reverse as it progresses again to a maximum and a minimum, completing the modulation cycle. The radio frequency phase reverses as first one tube and then the other of a pair becomes conductive. This phase reversal is necessary because when a target transmitter circumnavigates a directional system, such as an Adcock, only one section of the array reverses its phase when each quadrant is passed. Thus, if the phase of the other section were not reversed, voltages would be added instead of cancelled at points when nulls should occur.

The tubes of each pair are operated 180° out of phase in respect to each other, and one pair is operated 90° out of phase with the other. It is easy to tell at any point on the modulation schedule of Fig. 5 which tubes are conducting and at what gain. From this information and from the phase relations of the input lines 18 and 19, the occurrence of nulls may be determined. The following is the conduction schedule:

	Degree of Cycle	Tube Conducting
35	0°	14
	45°	14, 16
	90°	16
	135°	16, 15
	180°	15
	225°	15, 17
	270°	17
	315°	17, 14
40	$360^\circ (0^\circ)$	14

Let us assume a condition where the target transmitter is due north of the array (45° to the plane of both array sections 20, 21). Since the amplitude of the voltage induced in either section of the directional array is directly proportional to the cosine of the angle formed by the plane of the arriving wave front, and since the plane of the antenna pair is cut by the wave, the voltages would be .707 of their maximum possible value. However, each section of the array is intersected at 45° by the wave arriving from the north and, therefore, the same voltages will be obtained from each section of the array, the planes of the two sections of the array intersecting each other at a 90° angle. Thus, in the case of target transmitter north, and $E_1 = E_2$, i. e. the potentials applied over 18 and 19 are the same, we can derive the following information from the modulation schedule of Fig. 5:

Modulating Cycle in Degrees	Conducting Tube	E_p Out-put	Reason
65			
0°	14	>0	E_2 across R.
45°	14, 16	>0	$14=16$, $E_1=E_2$ (parallel across R).
90°	16	>0	E_1 across R.
135°	16, 15	0	$16=15$, $E_1=E_2$ (phases canceling in R).
180°	15	>0	E_2 across R.
70			
225°	15, 17	>0	$15=17$, $E_1=E_2$ (in parallel across R).
270°	17	>0	E_1 across R.
315°	17, 14	0	$17=14$, $E_1=E_2$ (phases canceling in R).
360°	14	>0	E_2 across R.

The foregoing shows how nulls occur for one

case over the modulation schedule and illustrates that with the conditions as given, two nulls would occur 180° apart; at 135° and 315°.

For other positions of the target transmitter, the point at which nulls should occur may be determined from the fact that for north the nulls are 135° and 315°. Actual null occurrence may be checked by referring to the modulation schedule and schematic. It will be found that:

Transmitter Position	Nulls Occur At—
North N. E. E. S. E.]	135° and 315°. 90° and 270°. 45° and 225°. 0° and 180°.

Reciprocal relations hold for the other major positions around the array.

While the foregoing "spot-checks" quite clearly illustrate the operation of the goniometer, checks on a few intermediate points will be given. Where the target transmitter is NNE:

$$E_2 - \cos 22.5^\circ = .924$$

$$E_1 - \cos 67.5^\circ = .382$$

One null for NNE should be 112.5° since NE is 90° and 270° and N is 135° and 315°.

Then at 112.5°:

Tube 15 conducts at .328 and 16 at .924. A null occurs since: $E_2 16G = E_1 15G$ (the voltages cancel in R), where 16G and 15G are gains of tubes 16 and 15.

The phase and amplitude of the transmission line voltages E_1 and E_2 are thus compared in the output resistor R. For any value of phase and/or amplitude of E_1 and E_2 there is a point on the modulation schedule which will produce a null as the resultants of these voltages appear in the output resistor R.

A few examples of theoretical conditions will be given to illustrate the action more fully. It is important that the device be in balance when no modulating voltages are applied. With no power applied to the goniometer and with E_1 and E_2 present in any values up to 100,000 microvolts, no noticeable voltage will appear across R, using a sensitive receiver of a few μ v. sensitivity. This is so because $C_1 = C_3$ and $C_2 = C_4$ within a fraction of one percent. The internal capacitances of the tubes are closely equal and are very small percentages of their output coupling capacitances.

When no power is applied to the goniometer, the resistor R is connected between the center tap of the capacitative voltage division system and a parallel resistive voltage division system.

This is best shown in Figs. 3a and 3b in which the same reference numerals are employed as in Fig. 3 except that C14 to C17 indicate the internal capacitances of the tubes 14 to 17. The capacitative voltage division system is composed of C17, C1, C3, and C16 in one section of the goniometer, and C2, C4, C14, and C15 in the other section of the goniometer. The parallel resistive voltage division system of one section comprises R and R2, and in the other section R3 and R4.

When no potential difference exists between the center taps of the two systems, i. e. resistive + capacitative systems, no potential exists across resistor R. When either tube of a pair becomes active upon the application of power to its plate circuit, the capacitative system becomes unbalanced in respect to the resistive system and the unbalance potential will develop across resistor R.

Reversing one set of transmission lines 18, 19

leading from the directional arrays 20, 21 causes the indicator pattern to shift 90°. Reversing the phase of M1, or M2 (modulation schedule change) likewise causes the pattern to shift 90° for a given connection of the transmission lines to the input of the goniometer.

This feature may serve to allow for the provision of a sense system for the goniometer by using a sensing antenna and suitably shifting the phase of either modulation voltage M1 or M2.

The cross connected input circuits necessitate to use chokes L1—L8 (Fig. 4) in the filament circuits to counteract the high capacity between the filaments and cathodes. Each filament is directly grounded over one choke L2, L4, L6 and L8, and is grounded also over filament by pass capacitor C18 through chokes L1, L3, L5 and L7.

The plate circuits have decoupling resistors R13—16 grounded over condensers C5—C12 to exclude R. F. from the modulator circuits.

A coaxial connection 22 is provided between the goniometer 13 and the signal receiver 7. With cables having a high balance ratio at the desired frequency, this cable may be made indefinitely long when terminated in its characteristic impedance.

The grid-cathode resistors R1, R2, R3 and R4 serve to produce the necessary bias. R9, R10, and R11 and R12 are plate load resistors.

The accuracy of the device depends mainly upon the maintenance of sine wave form modulation at a high degree of accuracy, the maintenance of a constant (90°) phase relation between the two modulating voltages, and the maintenance of a linear relationship between gain and plate potentials in the goniometer tubes.

What is claimed is:

1. In combination, an electronic goniometer divided into two sections comprising electric discharge devices, a directional antenna connected with each section, a source of sinusoidally varying modulating voltages applied out of phase to the two sections, an output load in which the phase and amplitude of the signals applied to the two sections is compared, and an indicator comprising a sine wave generator controlling said source of modulating voltages.

2. In combination, an electronic goniometer comprising two pairs of tubes, each having cathode, grid and anode electrodes, a directional antenna connected with the grids of each pair of tubes, a source of sinusoidally varying modulating voltages, connections from said source to apply said voltages to the plates of each pair of tubes 180° out of phase with respect to one another, and to one pair 90° out of phase with respect to the other pair, a connection from the cathode of one tube to the grid of its pair to permit operation of only one tube of a pair at a time, a resistance connected in multiple to the plates of the four tubes, a radio receiver connected to the last mentioned resistance, and an indicator comprising a sine wave generator controlling said source of modulating voltages.

3. In combination, an electronic goniometer comprising two pairs of linearly responsive tubes, each having cathode, grid and anode electrodes, a directional antenna system for each pair of tubes, balanced transmission lines connecting each system with the grids of its pair of tubes, resistance terminations for said lines having such low values that the grid resistance of one tube serves as the cathode resistance of its pair, a source of sinusoidally varying modulating voltages, connections from said source to apply said

voltages to the plates of each pair of tubes 180° out of phase with respect to one another, and to one pair 90° out of phase with respect to the other pair, a connection including a resistance from the cathode of one tube to the grid of its pair to permit operation of only one tube of a pair at a time and insure a shift bias and prevent the flow of grid current in the active tube, an output coupling condenser connected with the anode of each tube, a grounded resistance connected in multiple between the four output coupling condensers constituting a capacitative voltage division system, a radio receiver, a connection from said receiver to the last mentioned resistance shielded against direct pick-up of signals from sources other than from said grounded resistance, and an indicator comprising a sine wave generator controlling said source of modulating voltages.

4. In combination, an electronic goniometer comprising two pairs of tubes, each having cathode, grid and anode electrodes, a directional antenna connected with the grids of each pair of tubes, a source of sinusoidally varying modulating voltages, connections from said source to apply said voltages to the plates of each pair of tubes 180° out of phase with respect to one another, and to one pair 90° out of phase with respect to the other pair, a connection from the cathode of one tube to the grid of its pair to permit operation of only one tube of a pair at a time, a resistance connected in multiple to the plates of the four tubes, a radio receiver connected to the last mentioned resistance, an electronic indicator comprising an oscillator to produce a sine wave connected with said source of modulating voltages, two direct current amplifiers connected 90° quadrature to the oscillator, a cathode ray tube having vertical and horizontal deflecting means, connections from the output of each direct current amplifier to one of said deflecting means, and means for applying biasing voltages from output of said receiver to the direct current amplifiers.

5. In combination, an electronic goniometer comprising two pairs of linearly responsive tubes, each having cathode, grid and anode electrodes, a directional antenna system for each pair of tubes, balanced transmission lines connecting each system with the grids of its pair of tubes, resistance terminations for said lines having such low values that the grid resistance of one tube serves as the cathode resistance of its pair, a source of sinusoidally varying modulating voltages, connections from said source to apply said voltages to the plates of each pair of tubes 180° out of phase with respect to one another, and to one pair of 90° out of phase with respect to the other pair, a connection including a resistance from the cathode of one tube to the grid of its pair to permit operation of only one tube of a pair at a time and insure a shift bias and prevent the flow of grid current in the active tube, an output coupling condenser connected with the anode of each tube, a grounded resistance connected in multiple between the four output coupling condensers constituting a capacitative voltage division system, a radio receiver, a connection from said receiver to the last mentioned resistance shielded against pick-up of signals from sources other than said grounded resistance, an electronic indicator comprising an oscillator to produce a sine wave, an audio frequency amplifier connected with the output of said oscillator, a connection over which said am-

plifier controls said source of modulating voltages, a first and a second direct current amplifier, connections from the audio amplifier output to the direct current amplifiers, a phase shifter in one of the last mentioned connections to maintain them in 90° quadrature to one another, a cathode ray tube having vertical and horizontal deflecting means, connections from the output of one direct current amplifier to one deflecting means and from the other direct current amplifier to the other reflecting means, and means for applying biasing voltages from the output of said receiver to the direct current amplifiers to bias them to plate current cut-off conditions.

15 6. A goniometer having two electronic sections, said sections having multi-electrode discharge devices, an antenna connected with each section, a source of alternating current modulating voltage applied out of phase to the two sections, and means for maintaining a linear relationship between the gain and the modulating potentials of the two sections.

20 7. A goniometer having two electronic sections, each section having a pair of discharge devices, an antenna connected with each pair, a source of sine wave modulating voltage applied 90° out of phase to the two sections, and means for maintaining a linear relationship between the gain and the modulating potentials of the two pairs of devices.

25 8. A goniometer having two electronic sections, each section having a pair of multi-electrode discharge devices, two antennas, a balanced input from each antenna to a section periodically 30 to produce nulls therein and to vary the gain of said devices, a source of sine wave modulating voltage applied 90° out of phase to the two sections, means for maintaining a linear relationship between the gain and the modulating potentials of the two systems, and a resistor in 35 which the phase and amplitude of the input voltages of the two systems are compared.

40 9. An electronic bearing indicator comprising an oscillator to produce a sine wave, an audio frequency amplifier, connected with the output of said oscillator, a first and a second direct current amplifier, connections from the audio amplifier output to said direct current amplifiers, a phase shifter in one of said connections to 45 maintain them in 90° quadrature to one another, a cathode ray tube having vertical and horizontal deflecting means, connections from the output of one direct current amplifier to one deflecting means and from the other direct current amplifier to the other deflecting means, a radio frequency signal receiver, and means for applying biasing voltages from the output of said receiver to the direct current amplifiers to bias them to 50 plate current cut-off condition.

60 10. An electronic goniometer comprising two pairs of multi-electrode tubes, a directional antenna connected with a first electrode of each pair of tubes, a source of modulating voltages connected with a second electrode of each pair 65 of tubes out of phase with respect to each other, and to one pair out of phase with respect to the other pair of tubes, connections between the first and a third electrode of each pair of tubes to permit operation of only one tube of a pair at 70 a time, and an output load connected in multiple to the second electrodes of the two pairs of tubes.

75 11. An electronic goniometer comprising two pairs of multi-electrode tubes, a directional antenna connected with a first electrode of each

pair of tubes, an alternating current source of modulating voltages connected with a second electrode of each pair of tubes out of phase with respect to each other, and to one pair out of phase with respect to the other pair of tubes, connections between the first and a third electrode of each pair of tubes to permit operation of only one tube of a pair at a time, an output load connected in multiple to the second electrode of the two pairs of tubes, and an indicator controlled by the goniometer for controlling said source.

12. An electronic goniometer comprising two pairs of linearly responsive tubes, each having cathode, grid and anode electrodes, a directional antenna for each pair of tubes, balanced transmission lines connecting each system with the grids of its pair, a source of sinusoidally varying voltages, connections from said source to apply said voltages to the plates of each pair of tubes 180° out of phase with respect to one another, and to one pair 90° out of phase with respect to the other pair, a connection from the cathode of one tube to the grid of its pair to permit operation of only one tube of a pair at a time, an output coupling condenser connected with each plate, and a resistance connected in multiple to the four output coupling condensers.

13. An electronic goniometer comprising two pairs of linearly responsive tubes, each having cathode, grid and anode electrodes, a directional antenna system for each pair of tubes, balanced transmission lines connecting each system with the grids of its pair, resistance terminations for said lines having such low values that the grid

resistance on one tube serves as the cathode resistance of its pair, a source of sinusoidally varying voltages, connections from said source to apply said voltages to the plates of each pair of tubes 180° out of phase with respect to one another, and to one pair 90° out of phase with respect to the other pair, a connection including a resistance from the cathode of one tube to the grid of its pair to permit operation of only one tube of a pair at a time by insuring a shift bias and preventing the flow of grid current in the active tube, an output coupling condenser connected with each plate, and a resistance connected in multiple to the four output coupling condensers.
